SHOE AND METHOD OF MAKING SAME

Augustus Q. Williams, Weymouth, Mass.

Application November 24, 1933, Serial No. 699,523

3 Claims. (Cl. 12—142)

- This invention relates to the better grade of sport shoes and more especially to those in which unvulcanized rubber outsoles are incorporated.
- Shoes of this character have a leather upper, 5 an insole, and a rubber outsole which may be secured to the insole either by McKay stitching or by sewing the usual welt to the insole and upper and then stitching the outsole to the welt. The welt construction produces a shoe which is 10 superior to the McKay shoe in that it avoids the presence of a seam on the upper surface of the insole, but it is a considerably more expensive construction than the McKay shoe. With a view to reducing the expense of manufacture of such 15 a shoe, while still obtaining the advantage above mentioned of the welt type, I have made sport shoes of the general character above described by cementing the upper, insole and outsole together in the same general manner in which shoes having 20 outsoles made of leather and of certain compositions have been made heretofore. I have found it impossible, however, to produce a satisfactory union of a rubber outsole to the other parts of the shoe by this method. The chief 25 difficulty appears to be that the rubber cement which secures the outsole in place will not penetrate the leather insole, or the parts of the upper lasted over the edges of the insole, for a sufficient distance to produce a union having the requisite 30 strength. When such a shoe is being worn, the outsole is subjected to many strains that tend to separate it from the insole. After a time such separation actually takes place at points around the edges of the outsole and produces a condition 35 which is extremely unsatisfactory. This difficulty is especially pronounced in the case of shoes having crepe soles or other soles made of, or containing a high percentage of, unvulcanized rubber.
- 40 To devise a thoroughly practical solution for this problem constitutes the chief object of the present invention.
- The nature of the invention will be readily 45 understood from the following description when read in connection with the accompanying drawing, and the novel features will be particularly pointed out in the appended claims.
- In the drawing,
- Figure 1 is a perspective view of a shoe constructed in accordance with this invention, but showing the shoe in an uncompleted state; and 50 Fig. 2 is a transverse, vertical, sectional view through the forepart of the shoe illustrated in Fig. 1.
- 55 According to the method provided by this in-
- vention, the leather upper 2 is assembled on a last with an insole 3, preferably also of leather, and is lasted in the usual manner except that the lasted over margin of the upper preferably is secured to the insole by cement. The cements at 5 present used in the shoe trade are suitable for this purpose. Next, the bottom of the insole and the lower surfaces of the lasted over margins of the upper are sanded, scoured or buffed and the rubber outsole 4 then is secured to this bottom 10 surface by means of rubber cement. At some stage in this process, usually either just before or just after the outsole laying operation, the lower margin of the leather upper immediately 15 above the outsole is buffed, as indicated by the stippled stripe 5, Fig. 1, to remove the surface finish from substantially all of this area of the upper and to expose the underlying portions of the leather which have not been penetrated by the surface finishing materials. After the outsole has been laid, this buffed area of the upper 20 is coated with rubber cement. Preferably a rubber latex cement is used since it appears to penetrate more deeply into the portions of the leather underneath the buffed surface than do the cements made with volatile solvents. The cement is allowed to dry and later a rubber binder strip 6 is secured to the edge face of the outsole and to the cemented margin 5, the inner surface of the strip 6, the cemented margin 5 and the edge face 25 of the outsole being wiped with benzol, or some other rubber solvent, in order to make these surfaces sticky prior to applying the binder. In the preferred construction both the outsole and the binder are made of crepe rubber, and the procedure just described produces an exceptionally 30 strong union between the upper and the binder strip and cements the binder so firmly to the outsole that the two appear in the finished shoe 35 to be an integral piece. In applying the binder, as just described, it is usually cut of the proper width to fit around the heel, and consequently, is somewhat wider than is necessary around the forepart. Its upper edge, however, is properly positioned all around the shoe and the lower margin, where it projects below the tread face of the outsole, as indicated at a, Fig. 2, is later trimmed off.
- It has been definitely demonstrated in practice that this construction effectually overcomes 50 the difficulties heretofore encountered in making a shoe having a sole of unvulcanized rubber and in which the outsole is secured in position by cement. It will be observed that in the shoe above described the outsole is secured in place 55

not only by the cement joint between it and the insole, but also by the binder strip. Because of the manner in which this strip is joined to the leather upper and secures the edge of the outsole to this part of the shoe, a strong union is provided between these parts which is additional to that produced in a cemented shoe.

- 5 A further objection to shoes equipped with soles made of crepe rubber, or containing a high 10 percentage of unvulcanized rubber, is that they spread badly while being worn. I have found that if the binder strip 6 is applied to the shoe while under considerable tension, much of this 15 spreading difficulty is obviated and the sole retains its original shape much better than in prior 20 shoes of this type. In addition, a shoe made in this manner has a degree of flexibility considerably greater than that of the ordinary shoe of the cemented type.
- 25 While I have herein shown and described a preferred embodiment of my invention, it will be evident that the invention may be embodied in other forms without departing from the spirit or scope thereof.

- 25 Having thus described my invention, what I desire to claim as new is:
1. In a shoe, the combination of a leather upper, an insole to which the margins of said upper are secured, a crepe rubber outsole cemented to said upper and insole, and a crepe rubber binder strip extending around the shoe and cemented along one margin to the edge face of said outsole and along its opposite margin to the leather upper immediately above the outsole, whereby it

serves to bind said outsole and upper together, said binder strip being under tension and said outsole being held in its cooperative relationship to the other parts of the shoe solely by said binder strip and by the adhesive union of said outsole to other parts of the shoe.

5 2. That improvement in methods of manufacturing shoes which consists in securing a leather upper, an insole and a rubber outsole of a shoe together in their usual relationship, securing the 10 outsole in place by means of cement, at some stage in the process treating the margin of the upper immediately above the outsole to promote the penetration of cement into said margin, applying rubber cement to the surface so treated, 15 and cementing a binder strip, under tension, to the edge face of said outsole and to the cemented margin of the upper to provide an added bond between said upper and outsole.

20 3. That improvement in methods of manufacturing shoes which consists in securing a leather upper, an insole and a rubber outsole of a shoe together in their usual relationship, securing the outsole in place by means of cement, at some stage in the process treating the margin of the upper 25 immediately above the outsole to promote the penetration of cement into said margin, applying rubber latex cement to the surface so treated and cementing a rubber binder strip, under tension, to the edge face of said outsole and to the 30 cemented margin of the upper to provide an added bond between said upper and outsole.

AUGUSTUS Q. WILLIAMS.
